(57) **CLAIM**

The ornamental design for an interactive intelligent panel, as shown and described.

DESCRIPTION

FIG. 1 is a right front perspective view of an interactive intelligent panel showing our new design;

FIG. 2 is a left front perspective view thereof;

FIG. 3 is a right rear perspective view thereof;

FIG. 4 is a front view thereof;

FIG. 5 is a rear view thereof;

FIG. 6 is a left-side view thereof;

FIG. 7 is a right-side view thereof;

FIG. 8 is a top plan view thereof;

FIG. 9 is a bottom plan view thereof;

FIG. 10 is an enlarged right front bottom region view as taken from line 10 in FIG. 1 thereof;

FIG. 11 is an enlarged right front top region view as taken from line 11 in FIG. 1 thereof;

FIG. 12 is an enlarged left front bottom region view as taken from line 12 in FIG. 2 thereof;

FIG. 13 is an enlarged right rear bottom region view as taken from line 13 in FIG. 3 thereof;

FIG. 14 is an enlarged rear top region view as taken from line 14 in FIG. 3 thereof; and,

(Continued)

FIG. 15 is an enlarged rear middle region view as taken from line 15 in FIG. 3 thereof.

The evenly spaced broken lines immediately adjacent to the claim depict the bounds of the claimed design, while all other broken lines are directed to environment. In addition, the dot-dash broken lines indicating an enlargement portion of the design in FIGS. 1-3 that are illustrated in enlargements in FIGS. 10-15 form no part of the claimed design.
